CONTAINER FOR STORING LIPSTICKS OR THE LIKE

Roslyn C. Levine, 47 Winslow Road,
White Plains, N.Y. 10606

Filed June 28, 1967, Ser. No. 7,626

Term of patent 14 years

Int. Cl. D6—01; D28—03
U.S. Cl. D86—10

FIG. 1.

FIG. 2.

FIG. 3.

FIG. 4.

FIG. 1 is a perspective view of a container for storing lipsticks or the like, showing my new design;

FIG. 2 is a perspective side view thereof disclosing the container for storing lipsticks or the like in an inclined position while resting on the narrow side; and

FIG. 3 is a perspective side view thereof disclosing the container for storing lipsticks or the like in an inclined position while resting on the narrow side; and

FIG. 4 is a bottom plan view thereof.

The dominant features of my design reside in the portions shown in full lines.

I claim:

The ornamental design for a container for storing lipsticks or the like, as shown and described.
